CATHODE RAY TUBE

Leslie E. Flory, Oaklyn, and Arthur W. Vance,
Haddonfield, N. J., assignors to Radio Corpora-
tion of America, a corporation of Delaware

Application March 1, 1941, Serial No. 381,216

2 Claims. (Cl. 250—161)

This invention relates to thermionic discharge devices and, more particularly, to electron beam tubes, and has for its primary object to provide an improved device and method of operation for producing and controlling an electron beam.

In a cathode ray tube employing magnetic focussing use is usually made of an accelerating electrode in close proximity to the thermionic emitter to accelerate the electrons away from the emitter or to act as a masking aperture or to provide both functions. When such an accelerating electrode is used, a sharp curvature of the equipotential surfaces is introduced. This sharp curvature may give some of the electrons emitted from the cathode a high radial velocity producing a condition which makes it more difficult to focus the electron beam. The primary electrons may also strike the edges of the apertures, giving rise to secondary electrons which have a wide distribution in initial velocities and leave the aperture in random directions, resulting in further difficulties in focussing.

Another object of this invention is to eliminate the disturbance caused to the electron beam by the usual accelerating electrodes.

According to this invention, an extremely small electron source is provided with a large cylindrical electron accelerating element such that the electron beam produced does not suffer from the limitations introduced by the presence of apertures or small accelerating electrodes and does not require any electrostatic or magnetic focussing means.

Other and incidental objects of this invention will be apparent to one skilled in the art from a reading of the following specification taken in connection with the accompanying drawing in which—

Figure 1 shows a cross-sectional view of one form of this invention, and

Figure 2 is a cross-sectional view of a modification of Fig. 1.

Referring in more detail to Figure 1, an envelope 1 contains a heater element 3 which is enclosed in a cathode member 5 having therein a very small point of electron-emissive material 7. The structure of the cathode may take the form as shown and described in more detail in the George Patent 2,117,842 of May 17, 1938. A disc element 9 extends outwardly from the cathode.

A large cylindrical accelerating electrode 11 takes the form of a conducting coating flashed on the inner surface of the envelope 1 or it may be a cylinder supported adjacent the walls of the envelope 1 such that it extends between the cath-

ode 7 and the target electrode 13. The target electrode 13 comprises a translucent member supporting photoactive material 15. The target electrode 13 may take the form shown and described in the patent to Rose 2,213,174 of August 27, 1940.

Vertical deflecting coils 17 are provided such that the electron beam may be scanned in the vertical direction and similar deflecting coils 18 are provided for deflecting the electron beam in the horizontal direction.

A coaxial coil 19 is provided to maintain the electrons emitted from the point source 7 along in a beam which may be controlled by the deflection coils 17 and 18.

In the operation of the device, the cathode 5 may be either directly or indirectly heated. As the electron-emissive material 7 is heated, electrons tend to be emitted in all directions forward from the cathode 5. However, the magnetic field from the coil 19 causes the electrons emitted from the electron emissive source 7 to follow in a beam whose diameter remains substantially uniform and would normally follow along the axis of the uniform magnetic field produced by the coil 19.

The disc 9, which surrounds the cathode 5, leaving only a small area of the cathode exposed in the direction of the travel of the beam, is provided with a potential substantially equal to that of the cathode 5. The large cylindrical accelerating electrode 11 is charged with a positive potential such that it produces an electric field adjacent the cathode which is practically flat, so that the electrons from the emissive point source 7 are accelerated only axially. As a result, the only radial velocity of the electrons is that due to the initial velocities of thermionic emission, the effect of which is counteracted by the field from the coil 19.

A predetermined wave form may be applied to the deflecting coils 17 and 18 such that the electron beam will scan the mosaic electrode 13 at a predetermined rate.

If more than one large accelerating electrode is used, it is preferable that these be connected to increasing positive potentials until the maximum beam velocity is reached. Fig. 2 is a fragmentary view of the device, wherein a plurality of accelerating electrodes, 21, 22, 23, 24 are shown connected to progressively higher positive potentials derived from the source 25. Beyond this point in the tube, the beam may be allowed to strike a target such as shown by the target electrode 13, or a luminescent screen may be substi-

tuted. Instead of allowing the beam to strike the mosaic electrode 13 shown, at high velocity it may first be decelerated and utilized as a low velocity beam such as in the negative equilibrium type of Iconoscope otherwise known as Orthicon.

For the purpose of explanation, magnetic deflection has been shown. However, electrostatic deflection may be substituted without departing from the spirit of this invention.

While one system for carrying this invention into effect has been indicated and described, it will be apparent to one skilled in the art that this invention is by no means limited to the particular organization shown and described, but that many modifications may be made without departing from the scope of this invention as set forth in the appended claims.

We claim as our invention:

1. In combination, a thermionic tube including an element for producing electron rays by thermionic emission, magnetic means for maintaining said rays in a beam whose cross-sectional area remains substantially constant throughout

its length and whose cross-sectional area is substantially equal to the area of the electron-emissive area of said element, a target for said beam, means for causing said beam to scan said target, means for producing an electric field of increasing potential in a direction away from said element and whose equal potential areas are substantially flat in the region of the electron beam throughout its scanning range.

10 2. A thermionic tube including an electron emissive area for producing electron rays by thermionic emission, means for producing a substantially uniform magnetic field about said rays to concentrate said rays in an electron beam having 15 a substantially uniform cross-sectional area and whose cross-sectional area is substantially equal to the area of said electron emissive area, a target for said beam, means for causing said beam to scan said target, and means for producing an electric field whose equal potential areas are substantially flat in the region of the electron beam throughout its scanning range.
